UNITED STATES PATENT OFFICE.

FREDERICK VORCK, OF BROOKLYN, NEW YORK.

ARTIFICIAL CASCADE.

SPECIFICATION forming part of Letters Patent No. 356,054, dated January 11, 1887.

Application filed September 30, 1886. Serial No. 215,035. (No model.)

To all whom it may concern:

Be it known that I, FREDERICK VORCK, a citizen of the United States, residing at Brooklyn, in the county of Kings and State of New York, have invented new and useful Improvements in Artificial Cascades, of which the following is a specification.

This invention relates to a cascade which is constructed of a series of transparent plates, as pointed out in the following specification and claims and illustrated in the accompanying drawings, in which—

Figure 1 represents a plan or top view, partly in section. Fig. 2 is a side view, partly in section.

Similar letters indicate corresponding parts.

In the drawings, the letter A designates a transparent zigzag water-course, which is formed of a series of transparent plates, a, placed one above the other, and secured in vertical posts, b b.

By referring to Fig. 2 of the drawings it will be seen that the top plate starts from the outer edge of the post b and terminates at a short distance from the inner edge of said post, while the next plate below starts from the inner edge of the post b and terminates at a short distance from its outer edge, and so on, so that if water is poured upon the top plate it will flow in a zigzag course down from one plate to the other, and a cascade is obtained which produces a very good effect, particularly when illuminated at night. A still more striking effect is produced, however, by combining a series of the transparent water-courses A A' A² to A⁷ in such a manner that they form a closed

figure, such, for instance, as an octagon. In the center of this closed figure is situated a column, B, the outer surface of which presents reflecting-surfaces, and through the center of which rises the water supply pipe C. The pipe is provided with a head, D, from which extend a series of spouts, E E' E² to E⁷, one for each of the water-courses. The water flowing from the several water-courses collects in a basin, F, and passes off through the discharge-pipe G.

By placing lights of different colors into the space around the column B an extremely beautiful effect can be produced.

What I claim as new, and desire to secure by Letters Patent, is—

1. The combination, with a liquid supply and discharge pipe, of a vertical series of inclined transparent plates constructed to form a zigzag course for the liquid, substantially as described.

2. The combination with a series of transparent zigzag water-courses arranged to form a closed figure, of a central reflecting-column, a water-supply pipe rising through this central column, spouts extending from the water-supply pipe, one to each of the transparent water-courses, and a water-discharge pipe, substantially as described.

In testimony whereof I have hereunto set my hand and seal in the presence of two subscribing witnesses.

FREDERICK VORCK. [L. S.]
